UNITED STATES PATENT OFFICE

WILLIAM BARBER, OF BROOKLYN, NEW YORK

VALVE GRINDER

Application filed April 27, 1928. Serial No. 273,319.

This invention relates to new and useful improvements in grinding machines and has for its object to provide a device of this character particularly adapted for the grinding 5 of valve seats for poppet valves or the like.

A further object is to provide a grinder having a multiple grooved chuck, producing extended rectilinear motion and return by its revolutions.

10 Another object of this invention is the provision of a grinding machine adapted to grind poppet valves or the like wherein there are provided means to cause the valve being ground to rotate and reciprocate over 15 the surface of a grinding element.

Another object of this invention is the provision of worm threaded means whereby a poppet valve or the like which is to be ground may be rotated and reciprocated 20 across the rotating surface of a grinding block.

Another object of this invention is the provision of a grinding machine having 25 means for grinding a poppet valve which poppet valve is adapted by predetermined structural disposition to rotate and translate upon the surface of the grinding element.

Various other objects and advantages of 30 the invention than those above mentioned will appear more fully hereinafter. It is to be understood, that the specific forms shown are merely illustrative and hence the detailed 35 description thereof is not to be taken as limiting the invention itself.

The invention consists substantially in the combination, construction, location and relative arrangement of parts, all as will be more 40 fully pointed out hereinafter.

In the accompanying drawing:—

Figure 1 is a view in elevation

Figure 2 is a plan view

Figure 3 is a sectional view taken on line 3—3, Figure 2

Figure 4 is a sectional view taken on line 4—4, Figure 3

Figure 5 is a plan view, partly in section, of the multiple grooved, or, screw threaded holder.

50 Similar reference characters refer to simi-

lar parts throughout the various views of the drawing.

Heretofore various structures have been provided for the purposes of surfacing conically shaped poppet valves and the like. 55 Most of these structures, a typical one being that disclosed in the patent to Tryon, No. 1,602,135 dated October 5, 1926, have disclosed a structure wherein a given valve which is to be ground is brought to bear 60 against an emery wheel, or other type of grinding wheel, and is continually held in one position on the surface of that wheel. There, of course, has been provided means whereby the valve to be ground is rotatable 65 at the point on the grinding surface. However, no one of the patents in the past art has ever shown any means whereby the surface to be ground, that is, the surface of the valve which is to be ground, 70 may be made to move over the grinding element. It is the purpose of this invention to provide a structure and means therein contained wherein: (1) the valve surface 75 which is to be ground may continually be kept in contact with the grinding wheel: (2) wherein the valve surface which is to be ground may be made to move over the grinding element surface: (3) wherein there is provided means whereby the surface to be 80 ground on the valve may be varied due to means permitting of the rotation of the valve itself. It is obvious, of course, that in the art of grinding valves, and especially those using the gas engines, that the ground surface has heretofore been formed conically. 85 In the device as I recite it the operation, as the valve is reciprocated and rotated with reference to the holder hereinafter disclosed, results in that the angle in which the valve 90 is continually presented to the grinding wheel through the action of a spring, hereinafter disclosed, is constantly changing in each of its different positions of its reciprocating motion with the result that a somewhat 95 curved surface is ground over the portion of the valve and the usual beveled surface is dispensed with to the end that a more perfectly ground valve is obtained. The degree of curve given to the valve is, of course, a func- 100

tion of the relation existing between the speed of rotation of the poppet valve and the speed of rotation of the grinding wheel. There is no particular reason why the favored 5 conically shaped beveled surface around the periphery of the valve should be adhered to when a rounded surface may be readily attained, which is more perfectly ground and, therefore, will give a better valve action. If, 10 however, it be desired that a conical surface be yielded this can easily be attained by applying the machine herein disclosed to a poppet valve originally of substantial conical form and arranging the speed of rotation of 15 the valve so that it is of a predetermined small magnitude with respect to the speed of rotation of the grinding wheel. I, therefore, provide a manner and means hereinafter to be disclosed which will give me the desired 20 result.

Referring more particularly to the drawing in which like numerals refer to like parts throughout the specification. In the drawing above briefly described, I provide a frame 25 10 carrying a grinding element 12 and the tool or valve holding device 13. The grinding element may be of sandstone, emery carborundum, or, its equivalent, which is carried on a drive spindle 14. This spindle is 30 seated in a fine adjustment sleeve 15 in the frame 10. A pinion 16 on spindle 14 engages with drive gear 17 which is operated by handle 18. A clamp 19 provides means for fastening the device on work-bench or the 35 like. The valve and tool holding device is adjustably carried on an adjusting table 20 which is supported on frame 10 by arm 21. This arm is attached to the frame by a pivot joint 22, and permits axial adjustment on 40 the pivot bolt 23 to varying positions. A second pivot joint 24, at the end of the arm 21, carries the adjusting table 20. This table is provided with a slot 25 in which bolt 26 of tool holding device, or sleeve, 13 is held 45 slidably. This slot may be in alignment with the emery wheel in which case the valve 27 is in position for being dressed on its edge 28 in the manner stated below.

Within the holding sleeve is rotatively 50 mounted the chuck 29, which is held in position by set screw 30 engaging the worm groove 31 which extends from its forward end 31' to substantially three-fourths its length. The chuck is a straight walled tube 55 construction in which fit, from either end, the holding sleeves 32 for receiving and holding the stem 33 of the valve 27. The sleeves are split as is best shown in Figure 4, and by this means and the very gradual taper as is 60 best shown in Figure 3, the stem 33 is centered and firmly held for grinding as the chuck is rotated by means of the handle 34.

From the disclosure thus far given, the 65 operation of my device will be readily understood. The tool or valve stem is secured by

the sleeves 32 being pressed into the bore of the holding chuck. The entire assembly is then properly adjusted for either edge or face dressing as may be desired. By means of the handle 18 the grinding wheel is caused to rotate while the valve or tool is applied and, by means of a tensioning device 35, is firmly held in frictional contact thereto. As the grinding wheel is rotated, the valve or tool is caused to be rotated also, on its axis, by means of the handle 34, thereby properly dressing the valve, or tool, as the case may be. To the driving shaft 36, I have provided a squared shoulder to which may be secured power drive connections. 70 75 80

The construction herein disclosed not only provides a very economical device, but by its flexibility and independence of the operating parts, means are afforded whereby any part of the valve, or tool, may be given the proper dressing. The assembly of the valve stem and sleeves is quickly made and, without 85 assembling tools.

The simplicity of construction importance and efficiency of the operation of the chuck makes it one of the chief points of consideration in the invention. Its value will readily be appreciated when it is remembered that to produce a smooth, even finish on the tool, or instrument being polished, it is highly necessary that the contact surface of the grinding element be kept in a smooth even condition, and this can be done, only, by keeping the instrument being ground constantly moving back-and-forth across the grinding face of grinding element. This I accomplish by means of the worm groove, in the periphery of the chuck, engaging set screw in holding device and rotating, right and left by handle for said purpose. 90 95 100 105

As heretofore brought out the effect of the reciprocating motion combined with the rotative motion of the valve stem results in that the angle at which the valve is presented to the grinding wheel to the action of the spring 35 is constantly changing in each of its different positions of its reciprocating motion. Incidentally there results a ground surface which is somewhat curved over the ground portion of the valve with a curvature the degree of which depends upon the relative speeds of rotation of valve and grinding wheel. It is, therefore, apparent that the valve as ground has not the usual beveled surface, but I consider this to be of but small import when the high and fine degree of grinding that is thereby obtained is considered. It will be observed, therefore, that I have provided a novel means of grinding a valve and a novel construction therefor in conjunction with a novel method of correlating and allocating my various parts. Inasmuch as many changes may be made in the above construction and many apparently widely and different embodiments of the 110 115 120 125 130

scope of the invention may be made without departing from the spirit and scope thereof it is intended that all matter hereinabove contained or shown in the accompanying drawing shall be interpreted as illustrative and not in any way limiting. The following claims are intended to cover all generic and specific features of the invention described.

Having thus described my invention, what I claim as new and useful, of my own invention and desire to be secured by Letters Patent, is—

1. In a valve dressing mechanism a holding member comprising a tubing having a projection for pivotally and slidably mounting said tubing and a table having an elongated slot in which said projection is mounted, a threaded sleeve rotatably held within said tubing, a set screw secured to said tubing and adapted to work in said threaded sleeve, tapered expansion members fitting in said sleeve from opposite sides for engaging the stem of a valve or tube and a handle on said sleeve for rotating the same.
2. In a valve dressing mechanism a holding member comprising a tubing, a threaded sleeve rotatably held within said tubing, means mounted on said tubing adapted to work in the thread on said sleeve, a grinding element, tapered expansion members fitting in the sleeve from opposite sides for engaging the stem of a valve or tube, means on said sleeve for rotating the same, and means for rotating the grinding element.
3. In testimony whereof I have signed my name to this specification:—

WILLIAM BARBER.
